CLAIM

The ornamental design for a toner cartridge, as shown and described.

DESCRIPTION

FIG. 1 is a front, top, and right side perspective view of a toner cartridge in a first state;

FIG. 2 is a rear, bottom, and left side perspective view thereof;

FIG. 3 is a rear, top, and left side perspective view thereof in a second state;

FIG. 4 is a front elevational view thereof of FIG. 1;

FIG. 5 is a rear elevational view thereof;

FIG. 6 is a top plan view thereof;

FIG. 7 is a bottom plan view thereof;

FIG. 8 is a left side elevational view thereof; and,

FIG. 9 is a right side elevational view thereof.

The broken lines shown in the drawings illustrate portions of the toner cartridge that form no part of the claimed design.

1 Claim, 8 Drawing Sheets
